GRINDING WHEEL DRESSING TOOL

Fred M. Bley, Glenview, Ill.

Application June 28, 1945, Serial No. 602,027

11 Claims. (Cl. 125—11)

1

This invention relates to tools for dressing grinding wheels, and has to do with a tool specially suited for dressing grinding wheels the operative surfaces of which have profiles which comprise either flat surfaces or curved surfaces, or a combination of the two.

Tools for dressing grinding wheels having either flat surfaces or curved surfaces, or both, are known and extensively used. Such tools, in general, comprise a member having a cutting point of diamond or other suitable material highly resistant to abrasion, and means for imparting to the cutting point, in contact with the rotating grinding wheel, proper movements to dress the wheel to the desired profile. All of such tools, to my knowledge, are of rather complicated construction and operation, expensive, difficult to adjust and lacking in precision, particularly with respect to dressing arcuate surfaces and flat surfaces tangent to arcuate surfaces.

My invention is directed to the provision of a tool for dressing grinding wheels, which is of comparatively simple and inexpensive construction, may be accurately adjusted with expedition and facility, and is particularly suited to precision work, especially in dressing grinding wheels having profiles involving arcuate surfaces and flat surfaces tangent to arcuate surfaces. More specifically, I provide a shaft rotatable about a fixed axis and a carriage turnable with the shaft about such axis and having a rectilinear movement transversely of the shaft, the carriage being provided with a tool arm rigid therewith having a provision for mounting a tool with its cutting point in a plane radial to the shaft. By swinging the shaft through an arc of proper radius, with the carriage in centered position relative to the shaft, an arcuate surface, either concaved or convexed, of the grinding wheel may be accurately formed to the desired radius, and by moving the carriage transversely of the shaft, with the latter turned through the proper angle from its normal or zero position, a flat surface of the grinding wheel may be accurately formed with assurance that it will be tangent to and merge smoothly into the arcuate surface, whereby precision in the dressing of such a wheel is assured. The carriage is restrained against turning movement relative to the shaft, so that in order to dress a flat surface all that is required is to set the shaft at the proper angle and then move the carriage in proper direction transversely of the shaft, which is conducive to ease and accuracy of adjustment and precision in the dressing operation. In order further to facilitate

2

adjustment and assure precision, I provide means whereby the shaft may be locked in desired adjustment and adjustable stops for limiting turning movement of the shaft in either direction, whereby assurance is had that the adjustments of the cutting point and the travel of the carriage will be exactly the same in the final dressing operation as in the preliminary dressing operation, which assures precision in both operations and in the final result. Further objects and advantages of my invention will appear from the detail description.

In the drawings:

Figure 1 is a plan view of a tool embodying my invention;

Figure 2 is an outer end view of the tool of Figure 1;

Figure 3 is a sectional view taken substantially on line 3—3 of Figure 1, with the gauge member mounted in the tool arm for determining the position of the cutting point of the tool carried by the arm, certain parts being shown in elevation;

Figure 4 is a sectional view taken substantially on the line 4—4 of Figure 3, on an enlarged scale;

Figure 5 is a fragmentary sectional view taken substantially on line 5—5 of Figure 3, certain parts being shown in elevation;

Figure 6 is a fragmentary sectional view taken substantially on line 6—6 of Figure 2, certain parts being shown in elevation, on an enlarged scale;

Figure 7 is a fragmentary sectional view taken substantially on line 7—7 of Figure 2, certain parts being shown in elevation, on an enlarged scale;

Figure 8 is a diagrammatic view showing the manner in which the tool of my invention is used for dressing a grinding wheel having a profile comprising flat side surfaces tangent to a central surface of convexed arcuate form, the grinding wheel being shown fragmentarily;

Figure 9 is a diagrammatic view showing the use of the tool of my invention for dressing a concaved arcuate surface of a grinding wheel, the latter being shown fragmentarily; and

Figures 10 to 12, inclusive, are fragmentary views of grinding wheels of different profiles which have been dressed by the tool of my invention.

I have illustrated my invention, by way of example, as embodied in a tool intended for use with a magnetic chuck. The tool comprises a frame 15 of cast iron or other suitable magnetic material, of substantially L shape in side view,

having a base 16 and an upright support 17, the base being provided with suitably disposed pads or bosses for cooperation with the magnetic chuck. Support 17 is thickened at its central area to provide a hub 18 suitably bored for reception of opposed bearing collars 19 and 20 fitting snugly therein and secured in position by set screws 21 and 22, respectively.

A shaft 23, tapered outward of the upright support 17 for a considerable portion of its length, extends through hub 18 and is mounted for rocking or oscillatory movement in relatively narrow inwardly extending flanges 19a and 20a of the bearing collars 19 and 20, respectively. The flanges 19a and 20a are formed accurately to the taper of shaft 23 and support the latter in hub 18 in accurate centered relation thereto. It is quite difficult to machine a tapered bearing surface of substantial length to fit a tapered shaft to equal extent accurately and so as to assure that the shaft will be maintained on a fixed axis of rotation in all angular positions thereof, while also preventing any objectionable tilting or looseness of the shaft. By providing the bearing collars 19 and 20 with the flanges 19a and 20a, respectively, in restricted bearing contact with shaft 23, I avoid the difficulties referred to, since the relatively narrow bearing surfaces of the flanges 19a and 20a can readily be machined accurately to correspond to the taper of shaft 23. That assures that the shaft 23 is accurately centered in the hub 18 and will turn about a fixed axis in all angular positions thereof, while eliminating possibility of objectionable tilting or looseness of this shaft, which is important in a tool intended for precision work, such as the tool of my invention.

A mounting block 25, of dovetail section transversely and of rectangular form at its inner and outer faces, is fixed to the inner end of shaft 23, conveniently by being formed integral therewith, in centered relation thereto. This block 25 is provided at its inner face with a central inwardly extending interiorly threaded eye 26 fixed thereto, conveniently formed integral therewith, for a purpose which will be explained presently. The shaft 23 is provided, at the outer end of its tapered body portion, with a reduced stud 27 which extends through hub 28 of an operating arm 29, and through a thrust ring 30 seating at its radially outer portion against the outer end of hub 18 of support 17. Hub 28 of lever 29 is recessed from its inner face for reception of a ball-bearing structure 31 comprising an outer race 32 seating against the wall at the outer end of recess 33, an inner race 34 extending a slight distance inward beyond hub 28 and seating against the outer face of ring 30, and the intervening bearing balls 35, the race 32 fitting tightly about stud 27 and the race 34 fitting snugly but not tightly within the recess 33, and also fitting snugly but not tightly about the stud 27. The outer end portion 27a of stud 27 is threaded for reception of a nut 36 screwing thereon and seating against the outer end of hub 28, whereby the shaft 23, including stud 27 thereof, may be drawn into position seating snugly in the flanges 19a and 20a of the bearing collars 19 and 20, respectively, and lever 29 is held in position on stud 27, with the inner race 34 of the ball-bearing assembly 31 seating firmly against the outer face of thrust ring 30, with the areas of the lever extending radially outward from recess 33 spaced a slight distance from the outer face of the corresponding area of the thrust ring 30. A cap 76

nut 38 is screwed tightly on the outer end of portion 27a of stud 27 into contact with the nut 36 and, in cooperation therewith, guards against the latter nut being turned outward along the portion 27a of stud 27. The bearing structure 31 takes both axial and radial thrusts, and assures ease in turning or swinging the lever 29 in either direction for turning of the shaft 23 in desired directions. It will be clear that the shaft 23 is effectively restrained against endwise movement relative to support 17, and is mounted to rotate about a fixed axis $a-a$.

Stud 27 is provided with a flat 40 which is engaged by a flat ended set screw 41 threaded in hub 28 of lever 29, to assure that this lever will be mounted on stud 27 in predetermined angular relation thereto. The support 17 is formed concentrically with shaft 23 for the major portion of its periphery, and is provided on its edge with a scale 42 graduated in degrees and, if desired, in minutes, in opposite direction from a central zero mark coinciding with the vertical axial plane of shaft 23. A vernier index member 43 is set into and suitably secured to the upper end of lever 29 and extends therefrom inward over the scale 42, this member 43 bearing on its upper face a scale 44 also graduated in degrees and, if desired, in minutes, at opposite sides of the zero mark located on a radius of shaft 23 and on the lengthwise axis of lever 29. The lever 29 is provided, at its lower end, with a suitably formed outwardly projecting handle 45 to facilitate turning of the lever in desired direction and, a short distance above this handle, with a boss 46 suitably bored and tapped for reception of a locking screw 47 having a flat inner end engageable with the outer face of support 17 for locking lever 29 in angular adjustment about the axis $a-a$ of shaft 23, thereby also locking the shaft 23 in angular adjustment. The scale 42 and the vernier index member 43 cooperate to indicate the adjustment of lever 29 and shaft 23, as will be understood. In Figure 1 the zero mark of scale 44 is in register with the zero mark of scale 42, at which time the lever 29 is in its normal vertical position and the shaft 23 is in its normal position, which may be referred to as its zero position. The support 17 is provided with an arcuate boss 50 concentric with stud 27 and disposed in major portion therebelow, and with an arcuate slot 51 formed in boss 50 likewise concentric with stud 27, the end portions of boss 50 and of slot 51 extending upward a material distance above axis $a-a$ and the midlength of the boss and the slot being in the vertical plane of that axis. It will be seen that the slot 51 has an extent materially greater than 180° , for a reason which will be explained later. The slot 51 receives two hollow pins 52 corresponding in exterior diameter to the width of slot 51, each having at its inner end a head 53 providing a flange seating against the inner face of boss 50. Each of the pins 52 is suitably bored and tapped from its outer end for reception of a reduced screw stud 54 of a cylindrical stop member or post 55 seating at its inner end against the outer end or face of boss 50, post 55 being provided in its outer end with a diametrical slot or kerf 56 for reception of the blade of a screw driver or other suitable tool for screwing stud 54 tightly into pin 52, and thereby clamping post 55 to support 17 in any desired position along the slot 51. The posts 55 are disposed at opposite sides of the operating lever 29 and provide means for limiting,

to desired extent, swinging movement of that lever in either direction.

The flat 40 of stud 27 of shaft 23 is so disposed that the lengthwise axis of block 25 is in horizontal position, perpendicular to a plane passing through the zero mark or scale 42 and through axis *a—a*, when lever 29 is in its zero position with the zero mark of scale 44 in register with the zero mark of scale 42. A substantially cubiform carriage 58 is provided in its outer face with a lengthwise dovetail channel 59 which receives block 25, with a gib 60 disposed between the upper edge of block 25 and the upper wall of channel 59, this gib being held in position by socketed-head set screws 61 threading into carriage 58 adjacent the ends thereof and assuring a snug fit of the carriage 58 on block 25. The carriage 58 is thus slidably mounted on block 25 for lengthwise movement in either direction thereon, and has rectilinear movement transversely of shaft 23 while being restrained against turning movement relative thereto. Carriage 58 is further provided with a lengthwise groove 62 of substantially U shape in cross section, extending inward from groove 59 and closed at its ends by bosses 63 and 64. Groove 62 accommodates eye 26, and also accommodates a screw shaft 65 threading through eye 26. Shaft 65 is provided at one end with a reduced bearing stud 66 which fits snugly through the corresponding bore in boss 63, this stud 66 being provided at its outer end portion with a flat 67 which is engaged by the flat inner end of a socketed-head set screw 68 threaded through a stop collar 69 mounted on stud 66 in contact with the outer face of boss 63. Boss 64 is provided with a bore coaxial with the bore of boss 63 but equal in diameter to shaft 65, which is provided at its other end with an unthreaded portion 65a providing a bearing stud which seats in boss 64, shaft 65 being further provided with an integral collar 70 seating against the outer end of boss 64 and, outward beyond collar 70, with a squared stud 71. It will be seen that the shaft 65 may be inserted endwise through boss 64 and threaded through eye 26 until stud 66 is seated in boss 63 and the shoulder of the shaft at the inner end of this stud is in contact with the inner face of boss 63, after which stop collar 69 may be secured on stud 66, shaft 65 being then restrained against endwise movement in either direction. The squared stud 71 is adapted to be received in a corresponding socket in a socket element 72 of a crank 73 provided with a suitable handle 74. By rotating the shaft 65 in proper direction, by means of the crank 73, carriage 58 may be moved in either direction along the block 25. The carriage 58 is provided, on its upper face, with a scale 76 graduated from opposite sides of a central zero mark in inches and fractions thereof, for indicating the extent of movement of carriage 58 in either direction from its normal central or zero position. An index pointer 77, having its lower portion set in and fixed to block 25 at the outer face thereof, extends inward over scale 76 and cooperates therewith in an obvious manner. Adjacent scale 76, the carriage 58 is provided with a lengthwise vertical gauging surface 78 and, contiguous thereto, a lengthwise horizontal gauging surface 79, the purpose of which will be described later. The carriage 58 is also provided, at its midlength, with a vertical slot 80 the outer end portion of which opens, at its upper end, into groove 59, the inner portion of this slot being flared upward as shown. A latch lever 81 is pivoted in slot 80, on a pin 82 secured in carriage 58, this lever being of

a width, for the major portion of its length, to fit snugly in slot 80 so as to be restrained by the walls thereof against movement lengthwise of pin 82. The lever 81 is provided, at its outer end, with a 5 detent 83 of reduced width having an upwardly extending and upwardly tapering tip element 84 adapted to engage snugly in a corresponding notch 85 formed in the lower edge portion of block 25 at the midlength thereof. Lever 81 is urged in 10 latching direction by a compression spring 87 seating at one end against the upper end of a bore 88 in carriage 58 opening at its lower end into slot 80, the lower end of spring 87 seating on the upper face of lever 81 about a centering pin 90 secured in the lever. The inner end portion of lever 81 is of approximately semi-cylindrical shape and is knurled, at 92, to provide a good grip for manipulating this lever. It will be seen that the lever 81, in conjunction with detent 83 and tip element 84 and the compression spring 87, provides latch means for locking carriage 58 in accurately centered position to the block 25. In order to move the carriage 58 lengthwise along block 25, the inner end of lever 81 is raised, thus 15 disengaging detent 83 from block 25 and enabling movement of carriage 58 lengthwise of the block. After the carriage has been moved a short distance in either direction from its normal center position, the lever 81 may be released and detent 20 84 thereof is then held in contact with the lower edge of block 25, along which it slides in the movement of the carriage. Upon return of the carriage to centered position, the detent 84 automatically enters the notch 85 of block 25, again locking the carriage thereto in centered position. 25 In certain cases it may be desirable to have the carriage continue its travel beyond its central or zero position. To that end, the carriage is provided with a suitably disposed lengthwise bore 30 35 40 45 50 55 60 65 70 75 80a for reception of a holding pin 89b. By raising the lever 81 to its dotted line position indicated in Figure 3, and inserting pin 89b into position extending across slot 80, lever 81 is retained in its inoperative position, permitting continued travel of carriage 58 beyond its central position.

The underface of carriage 58 is flat or planar and seats accurately against the upper face of a boss or pad 93 at the outer end of a tool arm 94, conveniently formed of cast iron, suitably 50 secured, as by means of screws 95, to carriage 58 and rigid therewith. Arm 94 is thickened at its inner portion to provide a mounting boss 96 provided with two cylindrical openings 97 and 98 extending therethrough with their axes in the plane of the lengthwise axis of arm 94, which latter axis is disposed in a plane radial to axis *a—a* of shaft 23. When the operating lever 29 is in its normal or zero position, with base 16 of frame 15 in horizontal position, the openings 97 and 98 are disposed in vertical position with their axes intersecting the axis *a—a* of shaft 23, as will be clear from Figures 1 and 3. The opening 97 has associated therewith a socketed-head set screw 99 for adjustably securing therein a sleeve 100 in which is adjustably secured, by a set screw 101, a mounting member 102 having mounted therein, in a known manner, a cutting point 103 of a material highly resistant to abrasion, preferably a diamond. The opening 98 is adapted for reception of shank 104 of a gauge 105 adjustably secured by a set screw 99a and having, at the upper end of shank 104, a head 106 which extends a considerable distance to one side of shank 104 and the underface of which is 75 perpendicular thereto and is provided with a thin

layer or coating of a hard alloy, such as "stellite," 107. The upper face of boss 96 is accurately machined so as to be flat or planar and parallel with the axis $a-a$ of shaft 23, providing a gauging surface 108 which, in cooperation with the underside of head 106, provides means for accurately adjusting the distance from surface 108 to the tip of the cutting point, as will be explained presently. The sleeve 100 is provided with a lengthwise flat 100a engaged by the flat end of set screw 99, which facilitates centering of the diamond point 103 accurately on the axis of opening 97 and assures that sleeve 100 is secured firmly in position. It will be understood that suitable oil holes (not shown) may be provided for lubricating the various bearings and bearing surfaces, and preferably a sealing washer 110, of felt or other suitable material, is provided about the inner end of shaft 23 at the outer face of block 25, hub 18 of support 17 being suitably recessed for reception of the sealing washer or ring 110.

In Figure 8 I have illustrated diagrammatically the use of the tool of my invention for dressing a grinding wheel 112 having a profile comprising a central convexed area 113 curved on a regular arc extending an equal distance to each side of the central vertical plane $b-b$ of wheel 112, and two flat side surfaces 114 and 115 each disposed at an angle to and merging into the curved central area or surface 113. The wheel 112 is suitably mounted and rotated about an axis perpendicular to the axis $a-a$ of shaft 23, as is known. In setting up the dressing tool preliminary to the dressing operation, the gauge 104 is first adjusted so that surface 107 thereof is accurately spaced the proper distance away from gauge surface 108 of arm 94, this distance being accurately measured by a micrometer or other suitable instrument. In order to dress a convexed arcuate surface, the distance between the surfaces 107 and 108 should be less than the distance from surface 108 to axis $a-a$ of shaft 23 by an amount equal to the radius of the desired arc. The sleeve 100 is then adjusted until the tip of the diamond point 103 contacts surface 107 of the gauge, and is then secured firmly in position, after which the gauge is removed. After that has been done, particularly in the case of work requiring extreme accuracy, the setting of the tool is checked by gauges, in cooperation with the vertical and horizontal surfaces 78 and 79, respectively, of carriage 58, with the latter locked in centered position, for testing the accuracy of the setting with respect to the arcuate surface 113, with lever 29 in its zero position. In checking the setting for each of the flat surfaces 114 and 115, the lever 29 is turned through the proper angle at one side or the other of the axis $a-a$ of shaft 23, as indicated on the scale 42, and is locked in such position by the locking screw 47, the carriage 58 remaining locked to block 25 in centered relation thereto during the checking operation, it being understood that lever 29 also is locked in its centered or zero position during the operation of checking the setting of the tool with respect to the arcuate surface 113. Assuming the setting of the tool to be correct, the lever 29 is moved from its zero position over the scale 42 in one direction a distance equal to one-half of the length of the arc of surface 113, and is then locked in that position by the locking screw 47. The post 55, at the opposite side of the lower portion of lever 29, is then brought into contact with the lever and secured tightly in such position. The lever 29 is then moved in the opposite

direction from its zero position a distance equal to one-half of the length of the desired arc, as indicated by the scale 42, is locked in such position, and the other post 55 is moved into contact with the other side of the lower portion of the lever and secured firmly in position, as before. It will be seen that the two posts 55, thus positioned, constitute stops which limit swinging movement of the lever 29, and therefore limit movement of the diamond point 103 about the axis $a-a$ of shaft 23 to the length of the desired arc. After the setting of the tool has been tested and the proper adjustment has been made, as above, the dressing tool is positioned so as to bring the diamond point 103 into cutting engagement with the grinding wheel 112, which is then rotated at appropriate speed. By swinging the lever 29 through an arc, as permitted by the posts or stops 55, with the carriage 58 remaining locked to block 25 in its centered position, the diamond point 103 of the cutting tool is moved about the axis $a-a$ of shaft 23 through an arc of the same length as the desired surface 113 and dresses the central area of the wheel 112 accurately to the desired curvature. In order to dress the flat side surfaces 114 and 115, the dressing tool is withdrawn slightly from the wheel 112, sufficiently to provide clearance for the diamond point 103, and lever 29 is swung first to one side and then to the opposite side of its zero position, the posts 55 having first been released and moved into positions to clear the lever, through an angle corresponding to the angle of inclination of the flat sides 114 and 115, and the posts 55 are secured in proper positions to limit the swinging movement of the lever 29 in either direction to that angle. Assuming that it is desired to dress first the surface 114, the lever 29 is turned in clockwise direction, as viewed in Figure 2, until it contacts the left hand post 55, and is locked in that position by means of the locking screw 47. The carriage 58 is then released from block 25, by raising the inner end of latch lever 81, and is moved along block 25 toward the left, or downward as viewed in Figure 1, by rotating shaft 65 in proper direction, a distance equal to that required for dressing surface 114, as indicated on the scale 76. After the carriage 58 has been moved a short distance in that direction, the lever 81 may be released and thereafter the detent 84 bears upon and slides along the lower edge of block 25. The dressing tool is then positioned so that the diamond point 103 will be brought into cutting engagement with the wheel 112, which is rotated as before, and by turning shaft 65 in proper direction the carriage 58 is moved along block 25 toward its central or zero position. During such travel of the carriage the diamond point 103 dresses the surface 114 to the desired angle and, since the carriage 58 turns about the same axis as the diamond point 103—the axis $a-a$ of shaft 23—the surface 114 is tangent to and merges smoothly into the arcuate surface 113. In order to dress the surface 115, the lever 29 is swung into position in contact with the other post 55 and locked in that position, with the dressing tool remaining in operative relation to the wheel 112. In that connection, it should be noted that the carriage 58 is returned to centered position in the operation of dressing surface 114, in which position it is automatically locked by the latch lever 81 and associated parts. In order to dress the surface 115, carriage 58 is unlocked from block 25 and, by rotating shaft 65 in proper direc-

tion, is moved from its centered or zero position upward, as viewed in Figure 1, and toward the right, the diamond point dressing surface 115 accurately to the desired angle during such travel of the carriage and this surface, when thus dressed, being tangent to and merging smoothly into the arcuate surface 113. While the described procedure is not essential in dressing a grinding wheel such as that shown in Figure 8, it is preferred, though it will be understood that any other suitable procedure may be followed if desired. Preferably the grinding wheel is given a preliminary dressing in the manner stated, and is thereafter given a final dressing to assure precision. In the final dressing the diamond point or other cutting element should move in the same direction throughout the dressing operation, in order to avoid any inaccuracy due to slight wear of the shaft 55 and associated parts. In Figure 8 I have illustrated the final dressing operation, assuming that the cutting tool advances along the flat surface 114 in the direction indicated by the arrow *e*, then moves about the arcuate surface 113 about axis *a* as indicated by the arrow *f*, after which the cutting tool travels upward along the surface 115, as indicated by the arrow *g*.

In Figure 9 I have illustrated the dressing tool of my invention as used for dressing a concaved surface 116 on a grinding wheel 117. In this case the tip of the diamond point 103 is disposed above the axis *a* of shaft 23 a distance corresponding to the radius of the desired surface 116. In dressing this surface the posts 55 are disposed to limit swinging movement of lever 29 in either direction, as before, and by swinging the lever in clockwise direction, as viewed in Figure 2, from its extreme position in counterclockwise direction, the cutting tool is moved in the direction indicated by the arrow *h*, about the axis *a*, and the diamond point 103 dresses the surface 116 accurately to the desired arcuate curvature.

I have, for simplicity of description, illustrated the dressing tool of my invention as used, in Figures 8 and 9, for dressing grinding wheels having symmetrical profiles, and each having but one curved surface. It will be understood, however, that by disposing the dressing tool in proper relation to the grinding wheel and proper adjustment of the dressing tool, grinding wheels of a large variety of profiles—either symmetric or asymmetric, and having one or more curved surfaces, either concaved or convexed—may be accurately dressed by the tool of my invention. In Figures 10 to 12, inclusive, I have shown fragmentarily several grinding wheels of different profiles which have been dressed by the tool of my invention, and it will be understood that various other profiles may also be dressed by that tool. The slot 51 is of materially greater extent than 180°, as above noted. That is advantageous as enabling the dressing of clearances on the sides of a grinding wheel, by turning the lever 29 in either direction from its centered or zero position through an angle of more than 90°, into proper position for dressing the desired clearance surface.

It will be understood, as above indicated, that changes in construction and arrangement of parts of the dressing tool of my invention may be resorted to without departing from the field and scope of such invention, and I intend to include all such variations, as fall within the scope of the appended claims, in this application in which the

preferred form only of my invention has been disclosed.

I claim:

1. In a tool of the character described, a frame comprising a base and an upright support, a shaft mounted through said support for oscillatory movement about a fixed axis, an operating lever fixed to said shaft at the outer face of said support, a block fixed to the inner end of said shaft, a carriage slidable on said block for rectilinear movement transversely of said shaft and restrained against relative turning movement, a tool arm fixed to said carriage extending inward therefrom, means for moving said carriage in either direction on said block, means for locking said carriage to said block in predetermined relation thereto, and means carried by said lever for locking it to said support in desired adjustment about said axis.

2. In a tool of the character described, a frame comprising a base and an upright support, a shaft mounted through said support for oscillatory movement about a fixed axis, an operating lever fixed to said shaft at the outer face of said support, a block fixed to the inner end of said shaft, a carriage slidable on said block for rectilinear movement transversely of said shaft and restrained against relative turning movement, a tool arm fixed to said carriage extending inward therefrom, releasable means for automatically locking said carriage to said block at a predetermined position thereon, means for moving said carriage in either direction on said block beyond said position and locking it to said block throughout such movement, and means for locking said lever to said support in desired adjustment about said axis.

3. In a tool of the character described, a frame comprising a base and an upright support, a shaft mounted through said support for oscillatory movement about a fixed axis, an operating lever fixed to said shaft at the outer face of said support, a block fixed to the inner end of said shaft, a carriage slidable on said block for rectilinear movement transversely of said shaft and restrained against relative turning movement, a tool arm fixed to said carriage extending inward therefrom having a tool receiving opening disposed with its axis intersecting said fixed axis, spring latch means for locking said carriage to said block in position with the axis of said opening in the vertical plane of said fixed axis, means for moving said carriage in either direction on said block beyond said position and locking it to said block during such movement, and means for locking said lever to said support in desired adjustment about said axis.

4. In a tool of the character described, a frame comprising a base and an upright support, a shaft mounted through said support for oscillatory movement about a fixed axis, an operating lever fixed to said shaft at the outer face of said support, a substantially rectangular block fixed to the inner end of said shaft having at its inner face an inwardly projecting eye, a carriage slidable on said block for rectilinear movement transversely of said shaft and restrained against relative turning movement, a tool arm fixed to said carriage extending inward therefrom, said carriage having in its inner face a lengthwise channel receiving said eye, and a screw shaft in said channel threading through the eye rotatably mounted at its ends in said carriage and restrained against relative endwise movement.

5. In a tool of the character described, a frame

11

comprising a base and an upright support, a shaft mounted through said support for oscillatory movement about a fixed axis, an operating lever fixed to said shaft at the outer face of said support, a block fixed to the inner end of said shaft, a carriage slideable on said block for rectilinear movement transversely of said shaft and restrained against relative turning movement, a tool arm fixed to said carriage extending inward therefrom having a tool receiving opening disposed with its axis intersecting said fixed axis, means for moving said carriage in either direction on said block and locking it thereto during such movement, and means for locking said lever to said support in desired adjustment about said axis.

6. In a tool of the character described, a frame comprising a base and an upright support, a shaft mounted through said support for oscillatory movement about a fixed axis, an operating lever fixed to said shaft at the outer face of said support, a block fixed to the inner end of said shaft, a carriage slideable on said block for rectilinear movement transversely of said shaft and restrained against relative turning movement, a tool arm fixed to said carriage extending inward therefrom having a tool receiving opening disposed with its axis intersecting said fixed axis, means for moving said carriage in either direction on said block and locking it thereto during such movement, means carried by said lever for locking it to said support in desired adjustment about said axis, and adjustable stops on said support at opposite sides of said lever for limiting turning movement thereof in either direction.

7. In a tool of the character described, a frame comprising a base and an upright support, a shaft mounted through said support for oscillatory movement about a fixed axis, the upper portion of said support being concentric with said axis and having thereon a scale to indicate the extent of turning of said shaft in either direction, an operating lever fixed to said shaft at the outer face of said support carrying an index element cooperating with said scale, a block fixed to the inner end of said shaft, a carriage slideable on said block for rectilinear movement transversely of said shaft and restrained against relative turning movement, a tool arm fixed to said carriage extending inward therefrom, means for moving said carriage in either direction on said block and locking it thereto, during such movement, and means for locking said lever to said support in desired adjustment about said axis.

8. In a tool of the character described, a frame comprising a base and an upright support, a shaft mounted through said support for oscillatory movement about a fixed axis, an operating lever fixed to said shaft at the outer face of said support, a block fixed to the inner end of said shaft, a carriage slideable on said block for rectilinear movement transversely of said shaft and restrained against relative turning movement, a tool arm fixed to said carriage extending inward therefrom, means for moving said carriage in either direction on said block and locking it

thereto during such movement, means for locking said lever to said support in desired adjustment about said axis, and stops on said support at opposite sides of said lever adjustable concentrically with said axis and projecting outwardly of said support for limiting turning movement of said lever in either direction.

9. In a tool of the character described, a frame comprising a base and an upright support, a shaft mounted through said support for oscillatory movement about a fixed axis, an operating lever fixed to said shaft at the outer face of said support, a block fixed to the inner end of said shaft, a carriage slideable on said block for rectilinear movement transversely of said shaft and restrained against relative turning movement, a tool arm fixed to said carriage extending inward therefrom, means for moving said carriage in either direction on said block and locking it thereto during such movement, means for locking said lever to said support in desired adjustment about said axis, said support having therein a slot concentric with said axis, and stops adjustable in said slot at opposite sides of said lever disposed for contact thereby for limiting turning thereof in either direction.

10. In a tool of the character described, a frame comprising a base and an upright support, a shaft mounted through said support for oscillatory movement about a fixed axis, a block fixed to the inner end of said shaft, an inwardly projecting eye carried by said block, a carriage slideable on said block for rectilinear movement transversely of said shaft having in its inner face a lengthwise channel receiving said eye, a tool arm fixed to said carriage extending inward therefrom, and a screw shaft in said channel threading through said eye rotatably mounted in said carriage and restrained against relative endwise movement.

11. In a tool of the character described, a frame comprising a base and an upright support, a shaft mounted through said support for oscillatory movement about a fixed axis, a block fixed to the inner end of said shaft, an inwardly projecting threaded member carried by said block, a carriage slideable on said block for rectilinear movement transversely of said shaft having in its inner face a lengthwise channel receiving said member, a tool arm extending inward from said carriage, and a screw shaft in said channel having threaded engagement with said member rotatably mounted in said carriage and restrained against relative endwise movement.
